CAN CUTTER

Wayne Armstrong, Woodland, Calif.

Application May 29, 1950, Serial No. 164,867

5 Claims. (Cl. 30—249)

1

The present invention is directed to, and it is an object to provide, a novel device for splitting cans, which hold a nursery plant, from the upper rim to the can bottom at circumferentially spaced points whereby the can may be easily broken open for ready removal and transplanting of the plant.

Another object of the invention is to provide a can cutter which is relatively light-weight, portable, and convenient to use; the device being hand-supported and guided, but actuated in part by one foot.

A further object of the invention is to provide a can cutter which is operative to first break the upper rim of a can, and to then split or cut the can full length.

An additional object of the invention is to provide a can cutter which embodies a novel jaw assembly secured on the lower end of an upstanding handle, and a foot lever mounted in cooperative relation to said jaw assembly to actuate the latter.

It is also an object of the invention to provide a can cutter which is designed for ease and economy of manufacture; the device being simple in structure, but durable and strong.

Still another object of the invention is to provide a practical and reliable can cutter, and one which will be exceedingly effective for the purpose for which it is designed.

These objects are accomplished by means of such structure and relative arrangement of parts as will fully appear by a perusal of the following specification and claims.

In the drawings:

Fig. 1 is a perspective view of the can cutter as in use.

Fig. 2 is an enlarged side elevation of the can cutter; the jaw assembly being in open position.

Fig. 3 is a fragmentary side elevation of the can cutter, with the jaw assembly in closed position.

Fig. 4 is a top plan view of the device with the handle broken away.

Fig. 5 is a fragmentary cross section on line 5—5 of Fig. 3.

Referring now more particularly to the characters of reference on the drawings, the can cutter comprises an upstanding elongated handle 1 fitted, at its upper end, with a top cross bar 2 adapted for hand engagement whereby to manually support and manipulate the device.

At its lower end the handle 1 has a laterally facing mounting plate 3 fixed thereto, and such mounting plate projects some distance below the handle, as shown.

2

The front lower portion of the mounting plate 3 forms a fixed jaw 4 having a forward guide and cutting edge 5.

The numeral 6 indicates a generally bellcrank-shaped swinging jaw pivoted, intermediate its ends, as at 7, to the mounting plate 3 above the fixed jaw portion 4 of the latter.

As so mounted the swinging jaw 6 is movable from an open position, as in Fig. 2, to a closed position, as in Fig. 3; such swinging jaw including a rearwardly facing blade 8 having a relatively blunt upper cutting edge 9 and a sharp lower cutting edge 10.

The cutting edges 9 and 10 of the blade 8 are adapted to cooperate, in downwardly cutting relation, with the cutting edge 5 of the fixed jaw 4, upon swinging of jaw 6 between the aforesaid open and closed positions.

When the swinging jaw 6 is in its fully closed position, as in Fig. 3, a V-gap 11 remains between the extreme lower portions of the cutting edges 5 and 10 for the purpose hereinafter described.

A tension spring 12 connects between the rearwardly projecting leg 13 of the swinging jaw 6, and a lower point on the mounting plate 3, whereby said spring normally acts to urge said swinging jaw 6 to its open position.

A foot lever 14 is pivoted, intermediate its ends, as at 15, to the mounting plate 3 rearwardly of the tension spring 12 and below the swinging jaw leg 13; said foot lever 14 projecting some distance to the rear of said mounting plate 3 for ease of foot engagement.

The tip 16 of the foot lever 14 engages, in working relation, with the lower edge of said leg 13 toward the latter's rear end; such foot lever 14 including a two-way stop 17 thereon adapted to abut the rear end of the mounting plate 3 to limit the uppermost and lowermost positions of said foot lever. As the leg 13 works against the tip 16 of the foot lever 14, the spring 12, as it urges the leg 13 downwardly, similarly normally urges the foot lever 14 to its uppermost position, as in Fig. 2.

45 The above described can cutter is used in the following manner:

The user grasps the top cross bar 2 and manipulates the device until the upper rim 18 of a nursery can 19 is engaged to its limit into the then open jaw assembly; i. e. between the relatively blunt cutting edge 9 and the corresponding portion of the cutting edge 5, the latter edge lying flush against the outside of the nursery can 19.

The user then places one foot, as at 20, on 55 the foot lever 14 and depresses the latter, with

the result that the relatively blunt cutting edge 9 cuts or breaks through the upper rim 18 of the can 19.

Thereafter, with the foot lever 14 remaining depressed, with the jaw assembly then closed, as in Fig. 3, the entire device is pushed, by hand and foot, forcefully downward so that the side of the can 19 progressively rides into the V-gap 11 and is split apart by the adjacent cooperating portions of the cutting edges 5 and 10.

When the device reaches the floor 21 a downwardly projecting nub 22, on the lower edge of the mounting plate 3 directly below the fixed jaw 4, strikes said floor and prevents the blade 8 from coming into engagement with, and possibly being damaged by, the floor.

If the side of the nursery can 19 is relatively thick so that it cannot be split by slicing downwardly with said closed jaw assembly, as above described, then such jaw assembly may be scissored as the device is lowered. Such scissoring is accomplished merely by recurringly depressing and then releasing the foot lever 14.

The described can cutter is convenient to use, and provides a very practical device for cutting nursery cans from top to bottom, at circumferentially spaced points, to permit of breaking open of said can for removal of the plant 23 and its root system encased in earth 24.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A can cutter comprising an upstanding handle, a fixed jaw on the lower end of the handle having a forward cutting edge, a swinging jaw pivoted in connection with the fixed jaw having a rearward cutting edge, said cutting edges cooperating in downward cutting relation upon motion of the swinging jaw from an open position toward the fixed jaw, spring means tending to move the swinging jaw to open position, and a projecting foot lever pivotally mounted in connection with the fixed jaw and separate from but cooperating with the swinging jaw to cause motion of the latter from said open position toward the fixed jaw upon foot depression of said lever.

2. A can cutter comprising an upstanding handle, a laterally facing mounting plate fixed on the lower end of the handle, the front lower portion of said plate forming a fixed jaw having an upstanding forward cutting edge, a swinging

jaw pivoted to the mounting plate having a rearward cutting edge, said cutting edges cooperating in downward cutting relation upon motion of the swinging jaw from an open position toward the fixed jaw, and a foot lever pivoted on the mounting plate operative to cause said motion of the swinging jaw.

3. A can cutter comprising an upstanding handle, a laterally facing mounting plate fixed on the lower end of the handle, the front lower portion of said plate forming a fixed jaw having an upstanding forward cutting edge, a swinging jaw pivoted to the mounting plate having a rearward cutting edge, said cutting edges cooperating in downward cutting relation upon motion of the swinging jaw from an open position toward the fixed jaw, the swinging jaw being of generally bellcrank shape including a rearwardly extending leg, and a foot lever pivoted on the mounting plate with the forward end of said lever in working engagement under said leg and with the rear end projecting from said mounting plate.

4. A can cutter comprising an upstanding handle, a laterally facing mounting plate fixed on the lower end of the handle, the front lower portion of said plate forming a fixed jaw having an upstanding forward cutting edge, a swinging jaw pivoted to the mounting plate having a rearward cutting edge, said cutting edges cooperating in downward cutting relation upon motion of the swinging jaw from an open position toward the fixed jaw, the swinging jaw being of generally bellcrank shape including a rearwardly extending leg, and a foot lever pivoted on the mounting plate with the forward end of said lever in working engagement under said leg and with the rear end projecting from said mounting plate; there being a spring connected to the swing jaw tending to open the same and to move said leg downward, and stop means between the foot lever and mounting plate operative to limit both upward and downward motion of said foot lever.

5. A can cutter, as in claim 3, including a nub projecting downward from the lower edge of the mounting plate, adjacent its cutting edge, to a point below the lower end of the swinging jaw when the latter is in closed position.

WAYNE ARMSTRONG.
